UNITED STATES PATENT OFFICE.

MAX GOLDMAN, OF LOS ANGELES, CALIFORNIA.

DESIGN FOR A BOW-TIE RACK.

Application filed February 24, 1927. Serial No. 20,887. Term of patent 3½ years.

To all whom it may concern:

Be it known that I, MAX GOLDMAN, a citizen of the United States, residing at Los Angeles, in the county of Los Angeles and State of California, have invented a new, original, and ornamental Design for Bow-Tie Rack, of which the following is a specification, reference being had to the accompanying drawing, forming part thereof.

Fig. 1 is a top plan view of a bow tie rack showing my new design; and
Fig. 2 is a front elevation thereof.

I claim:
The ornamental design for a bow tie rack as shown.

MAX GOLDMAN.
